UNITED STATES PATENT OFFICE

WILLIAM R. MOORE, JR., OF HAGERSTOWN, MARYLAND, ASSIGNOR TO DECA-DISC PHONOGRAPH COMPANY, OF WAYNESBORO, PENNSYLVANIA, A CORPORATION OF PENNSYLVANIA

LOUD-SPEAKER

Application filed December 2, 1929. Serial No. 411,157.

This invention relates to loud speakers for phonographs and radios and the object of the invention is to construct or mount a loud speaker so that it will resemble in outward appearance a pipe organ. While it is designed primarily for use with a phonograph in which pipe organ records will be played so that the whole effect will be that of a pipe organ playing, nevertheless it may be connected to a radio and readily operated by conventional radio pick-up.

The purpose of the invention is to simulate a pipe organ to produce a harmony of appearance to add to the pipe organ music.

15 A further object is to so modify the loud speaker as to add considerable resonance to the tones and better the tone quality of the instrument.

Referring to the accompanying drawing 20 which is made a part hereof and on which similar reference characters indicate similar parts,

Figure 1 is a front view of the loud speaker and its mounting,

25 Figure 2 is a side view of the same, and

Figure 3 is a section on line 3—3 of Figure 1.

In the drawing numeral 10 indicates any suitable base built to resemble in miniature the base of a pipe organ and numeral 11 indicates a plurality of resonant pipes mounted on the base and arranged somewhat in semi-circular position with a loud speaking cone 12 positioned to the rear of the pipes and if desired secured to them by means of brackets 14 as shown in Figure 3 or in any other suitable way. The loud speaker may be connected electrically by means of wires 13 both to a remote control unit and to mechanism for reproducing sound from a record, such as, for example, the remote control mechanism shown in my copending application Serial No. 241,931, filed December 22, 1927. While the unit will obviously be designed for use with a phonograph in which only pipe organ records will be played to give the full effect of a pipe organ in the room obviously the loud speaker unit may be connected to a radio, particularly when pipe organ music is played on the radio so as to reproduce in

the room the pipe organ music with the full effect that would be obtained if a pipe organ itself were played in the room.

In actual use I have found that the arrangement of the organ pipes, as indicated, not only gives the appearance of a pipe organ but that the pipes give added resonance to and increase the tone quality of the instrument.

It will be obvious to those skilled in the art that various changes may be made in my device without departing from the spirit of the invention and therefore I do not limit myself to what is shown in the drawing and described in the specification, but only as indicated in the appended claims.

Having thus fully described my said invention, what I claim as new and desire to secure by Letters Patent, is:

1. The combination with a loud speaker of a plurality of vertical pipes arranged in arcuate formation in front of the loud speaker and secured thereto, a base having a group of said plurality of pipes mounted at each end and a pedestal positioned on and set back from the edge of said base, said pedestal supporting a group of said pipes between the said end groups, substantially as set forth.

2. A support for a loud speaker cone comprising a base having an arcuate shape, a group of tubes arranged at each end of the base, said tubes being rigidly secured to and vertically mounted on the base, an arcuate pedestal mounted on the base between said groups of tubes, said pedestal having a group of vertical tubes secured to and mounted thereon, all of said tubes being secured to the rim of the said cone, substantially as set forth.

3. The combination with a loud speaker of a plurality of tubes arranged adjacent the outlet side of the speaker in arcuate formation, said tubes being spaced apart to provide apertures for the exit of sound waves from the loud speaker and to break up the sound waves to vary the tone quality of the sound issuing from the loud speaker, substantially as set forth.

4. The combination with a loud speaker cone of a plurality of resonant pipes ar-

ranged in front of and secured to the loud speaker, said pipes being spaced apart to provide apertures through which sound waves from the loud speaker may issue, the pipes further serving to add resonance to and change the quality of the sound waves issuing from the loud speaker, substantially as set forth.

10 In witness whereof, I have hereunto set my hand at Waynesboro, Pennsylvania this 23rd day of November, A. D. nineteen hundred and twenty-nine.
